CLAIM

We claim the ornamental design for a tilt latch, as shown and described.

DESCRIPTION

FIG. 1 is a side view of the tilt latch of the present invention; FIG. 2 is an end view of the tilt latch of FIG. 1 taken from the right side of FIG. 1;

FIG. 3 is a side perspective view of the tilt latch of FIG. 1; FIG. 4 is a side perspective view of the tilt latch of FIG. 1 taken from the side opposite the side shown in FIG. 3;

FIG. 5 is a top perspective view of the tilt latch of FIG. 1;

FIG. 6 is an end view of the tilt latch of FIG. 1 taken from the side opposite the end of FIG. 2;

FIG. 7 is a top view of the tilt latch of FIG. 1; and,

FIG. 8 is a side view of the tilt latch of FIG. 1 taken from the side opposite the side of FIG. 1.
